US00D858566S

(12) **United States Design Patent** (10) **Patent No.:** **US D858,566 S**
Bacchus (45) **Date of Patent:** **** Sep. 3, 2019**

(54) **DISPLAY SCREEN OR PORTION THEREOF WITH GRAPHICAL USER INTERFACE FOR VIDEO AND REPETITION RECORDING**

(71) Applicant: **WARP Lab, Inc.**, Magnolia, TX (US)

(72) Inventor: **Akil Bacchus**, Magnolia, TX (US)

(73) Assignee: **WARP Lab, Inc.**, Frisco, TX (US)

(**) Term: **15 Years**

(21) Appl. No.: **29/627,886**

(22) Filed: **Nov. 30, 2017**

(51) **LOC (12) Cl.** **14-04**

(52) **U.S. Cl.**

USPC **D14/488**
